UNITED STATES PATENT OFFICE.

GEORGE W. GUTHRIE, OF EMSWORTH BOROUGH, PENNSYLVANIA.

TRAP-NEST.

1,209,699.

Specification of Letters Patent. Patented Dec. 26, 1916.

Application filed February 12, 1916. Serial No. 77,881.

To all whom it may concern:

Be it known that I, GEORGE W. GUTHRIE, a citizen of the United States, residing at Emsworth borough, in the county of Allegheny and State of Pennsylvania, have invented certain new and useful Improvements in Trap-Nests, of which the following is a specification.

My invention relates to improvements in trap nests, of the kind used for poultry, and particularly laying hens, for the purpose of keeping an accurate record of the egg product of each individual hen.

Trap nests of various kinds have been manufactured and used in which the nest cavity is provided with trap doors of different kinds for the purpose of automatically entrapping the hen until released, and also in connection with a signal device intended to be actuated by the weight of the hen, and of the egg, when laid, in connection with a relatively movable portion of the nest itself, as in the prior patent of Schlie, No. 700245.

My invention has in view to provide a nest having an automatically operable entrance closure, an oppositely located door, an extended egg receptacle of such reduced cross section as to admit the egg only, means actuated by the weight of an egg for operating signal mechanism, means for providing access for removal of the egg, and various other features of construction and operation as more fully hereinafter described.

Referring to the drawings Figure 1 shows one preferred form of the invention, in vertical section, and showing an egg deposited in the receiving receptacle. Fig. 2 is a partial similar view, showing the egg support and contact mechanism in normal open position. Fig. 3 is a face view of the nest in elevation, partly broken away. Fig. 4 is a detail view of the door latching and holding device.

The nest cavity 2, which is preferably rectangular in cross section, is inclosed within surrounding walls of any suitable material, as wood, sheet metal, or the like, and is provided with a suitably shaped nest 3, lined with any adaptable soft material, as indicated. At the entrance side of the nest I provide an opening 4 adapted to be closed

by a door 5 hinged at 6 and provided with any suitable lifting handle 7. It is designed that the door may be set in partly open position, as indicated in Fig. 1, and to be thus held by means of a pivoted supporting latch frame 8, which may be of wire or other suitable material, pivoted to each side portion of the door at 9. The latch frame 8 is provided across its inner end with a transverse bar 10, the ends 10' of which are adapted to be seated in a holding socket 11, at each inner side of the nest frame, and preferably forming a portion of an inclined flange 60 guide 12. At the upper end of said guide, at each side, are similar sockets 13, into which the rod terminals 10' will seat when the door 5 is closed upon entrance of the fowl, as indicated in dotted lines in Fig. 1. 70 At the outer portion of the tilting frame 8 it is provided with a lifting latch 14 of any suitable construction, by which it may be raised out of engagement with either notch 11 or 13, for the purpose of manipulating 75 the door in either opening or closing. A supplemental socket 15 adapted to engage the rod terminals 10' and hold the door in fully raised position, as indicated in dotted lines, may also be provided, when it is desired to 80 raise and support the door entirely, as for cleaning, etc. The several sockets 11, 13 and 15 are formed by bending the edges of a triangular shaped sheet metal plate, as indicated, to form comparatively narrow 85 flanges extending at right angles to the plate, which is secured against each inner opposite side of the nest box.

The nest may be mounted as a wall nest, in which case the side opposite the entrance opening may be entirely closed; or it may be mounted as an individual unit, or in a continuous row of units, with ample space at the other side, in which case, if desired, I provide a supplemental door 16 hinged at 17, capable of being opened or closed, and preferably leaving a light or air clearance space 18 at the upper edge thereof. An entrance platform 19 of any suitable kind may be provided as desired, it being understood that the top portion of the nest is covered by any suitable closure, as a board or plate 20.

A reduced circular opening is provided at

the central lowest portion of the nest 3, downwardly beyond which extends the egg receptacle 21, of just sufficient cross section to freely and easily receive the egg as laid, 5 and not sufficiently large to easily admit of the entrance of the foot of the fowl, the cavity also being sufficiently deep to allow the egg to fall well below the top of its entrance. Said cavity is surrounded and 10 formed by any suitable inclosing frame 22, either cylindrical or square in cross section, as preferred, and also having an interior soft lining substance similar to the lining of the nest, as indicated. A door 23 at one 15 side of the cavity framing 22 admits of access to the interior for removal of the laid egg, and may be provided with a suitable hasp 24 and lock, as preferred. At the bottom portion of cavity 21 is a resiliently 20 mounted receiving pan 24, preferably also provided with a soft lining material over its upper face, mounted on a spring arm 25, and adapted to be maintained normally in the upward receiving position indicated in 25 Fig. 2, and to be depressed by the weight of the egg *a*, as indicated in Fig. 1.

The pan 24, or resilient arm 25, is provided with a contact terminal 26 adapted to engage and close a circuit through a co-acting contact terminal 27. Each of said terminals 30 26 and 27 is connected with a conductor 28 and 29 respectively, in circuit with an alarm device 30 and a battery 31, whereby to give a signal at any desired location, upon depression of the pan 24, as will be readily understood. The signal may be utilized in connection with an indicating device showing 35 the number of the particular nest, or laying house, which may then be visited, the egg removed, and the fowl released. At the same time note is made of the particular fowl, as by a numbered tag which may be attached to its leg or elsewhere, as is a common practice, thereby facilitating the keeping 40 of the daily record, and enabling the particular crediting of the daily product of a flock of hens to be individually maintained.

The door 5 is automatic in its operation 50 in that the cross bar 10 is located at a distance above the bottom of the entrance opening 4 sufficiently low to insure the lifting of it by the back or tail of the fowl on entering, whereby the weight of the door will cause it to fall behind her to closed position, the bar 10 becoming seated in sockets 13, thus entrapping the fowl until released. Any suitable means may be employed to limit the downward movement of frame 8 55 as by providing ordinary strap pivoting hinges 32 off-set at their outer sides, providing limiting shoulders 33 for arresting the angular corner portions of arms 8.

The amount of light, and the location of

the light aperture 18 may be properly graduated and controlled so as to insure a desirable degree of darkness within the nest, the light and air supply being preferably located at the side opposite the entrance, as shown. 65

An especial advantage of the door 16, when the nest has clearance at each side, is that it may be opened for removal of the fowl and for re-setting of the door 5 to raised position, instead of using the door 5 75 for removal from the opposite side, as when the device is employed as a wall nest.

The construction and operation of the invention will be readily understood and appreciated from the foregoing description. 80 The hen having entered the nest and being entrapped, upon laying the egg will arise from her sitting posture to seek exit through the open light space 18, thereby freeing the egg and allowing it to easily and gently roll 85 or fall into the centrally arranged depressed receiving chamber 21. The said chamber is a rigid portion of the main nest construction, and because of its stationary character and location, provides a completely protective receptacle for the egg, avoiding its injury by crushing and completely isolating 90 it from the main nest chamber.

What I claim is:

1. A trap nest of the class described having 95 a main nesting chamber, and an entrance door thereto provided with a transverse adjustable holding arm operable by upward pressure, and having a supplemental lifting terminal, and receiving sockets 100 for said arm on the side walls of the nest.

2. A trap nest of the class described having 105 a main nesting chamber, and an entrance door thereto provided with a transverse adjustable holding arm operable by upward pressure, and receiving sockets for each end of said arm adapted to engage the arm at different positions and to positively hold the door either open or closed.

3. In combination with a nest construction 110 of the type described having an entrance opening, a pivotally mounted closing door, a supporting frame pivoted to the door having an externally extending lifting terminal and an internally extending transverse locking arm, and a plurality of sockets on the side walls of the nest adapted to engage and hold said arm and the door in varying positions.

4. In combination with a nest construction 115 of the type described having an entrance opening, a pivotally mounted closing door, a supporting frame pivoted to the door having an externally extending transverse lifting terminal and an internally extending locking arm, and sockets on the sides of the nest adapted to engage and hold said arm at 120 a position above the bottom of the entrance

opening adapting the arm to be released by upward pressure of a fowl upon entering the nest.

5. In a nest of the class described, a chamber-inclosing casing having an entrance opening and a door therefor, and provided at its lower portion with a nest compartment having at its central portion a downwardly extending egg receptacle of reduced area ap-

proximating the dimensions of an egg, and 10 provided with a relatively movable bottom having a depressible supporting spring.

In testimony whereof I hereunto affix my signature in the presence of two witnesses.

GEORGE W. GUTHRIE.
